UNITED STATES PATENT OFFICE.

ISAAC W. CRABTREE, OF CAIRO, ILLINOIS.

FAN ATTACHMENT FOR SWINGS.

RECEIVED AND MAILED COPY

1,239,161.

Specification of Letters Patent.

Patented Sept. 4, 1917.

Application filed September 23, 1916. Serial No. 121,793.

To all whom it may concern:

Be it known that I, ISAAC W. CRABTREE, a citizen of the United States, residing at Cairo, in the county of Alexander and State 5 of Illinois, have invented certain new and useful Improvements in Fan Attachments for Swings, of which the following is a specification.

This invention relates to certain new and 10 useful improvements in fan attachments for swings and it has for its objects among others to provide a simple, cheap, yet efficient device readily attachable to any swing and so constructed that the swinging movement of the swing proper gives constant 15 revolution to the fan always in the same direction.

It has for a further object to provide efficient means for insuring ease of operation 20 and avoiding damage to the mechanism by reason of overwrapping of the cords upon their drums.

Other objects and advantages of the invention will hereinafter appear and the 25 novel features thereof will be particularly pointed out in the appended claims.

The invention is clearly illustrated in the accompanying drawings, which, with the numerals of reference marked thereon, 30 form a part of this specification, and in which—

Figure 1 is a side elevation, with portions broken away, of a lawn swing with my present improvements applied thereto.

Fig. 2 is a cross section on the line 2—2 of Fig. 1, looking in the direction of the arrows.

Fig. 3 is a diagrammatic view showing the swing moving in one direction.

Fig. 4 is a similar view showing the swing as moving in the opposite direction.

Fig. 5 is a sectional detail taken in line with the fan shaft, with parts broken away and parts shown in elevation.

Fig. 6 is a cross section on the line 6—6 of Fig. 7, looking in the direction of the arrows.

Fig. 7 is a section on the line 7—7 of Fig. 6, looking in the direction of the arrows.

Like numerals of reference indicate like parts throughout the several views.

Referring to the drawings,

1, 1 designate the uprights or supports of the swing, of any ordinary or approved 55 form of construction, suitably braced to give the requisite strength, and 2, 2 are the

pendent swinging uprights, two upon each side of the swing, and pivotally mounted at their upper ends, as at 3, 3, in any suitable manner to the upper ends of the supports 1, 60 as shown clearly in Fig. 1. The platform, the seats and the side arms of the swing may be of any well-known or approved form of construction and form no part of the present invention.

In addition to the cross braces 4 at the top, the supports 1 are additionally braced by the transverse brace members 5 and secured to these cross braces 5 at substantially their midlength are the bearings 6 for a 70 shaft 7. On this shaft are loosely mounted the drums or spools 8, one near each end, and between these spools the fan blades 9 are affixed to the shaft. These blades may be of any well-known or preferred form of 75 construction attached to the shaft in any suitable manner.

Each spool 8 comprises a body portion with a flange 10 at one end against which bears a washer 11, a cotter pin 12 passing 80 through the shaft and engaging the washer and serving to limit the endwise movement of the spool on the shaft. The other end of the spool has an enlargement, as shown at 13, within which is a chamber 14, the inner 85 wall of which is constructed in the form of a clutch member having the curved cam surfaces 15, in the present instance shown as three in number, and the abrupt shoulders 16, of like number, as seen clearly in Fig. 6. 90 Coöoperating with these curved surfaces and abrupt shoulders is a pin 17 loosely endwise movable through a transverse opening in the shaft 7 and engageable with the curved cam surfaces or the abrupt shoulders according to conditions.

A plate 18 covers the outer open end of this chamber, as seen best in Fig. 7, the same being held in place by a cotter pin 19 or the like passed transversely through the 100 shaft.

The shaft 7 is mounted for limited endwise movement in its bearings, being limited in such movements by cotter pins or the like 20 passed transversely through the shaft 7 105 adjacent the ends of the spools and bearings.

21 is a cord having a plurality of winds around the one spool 8 and its opposite ends attached in any suitable manner, as at 22, to the opposed pendent members 2 upon one 110 side of the swing. In the present instance I have shown clamps 23 embracing these mem-

bers 2 and having eye-bolts 24 with adjusting nuts 25 as a means of attachment of the ends of the cord permitting adjustment when necessary.

5 26 is another cord wrapped a number of times around the opposite spool 8 and having its ends attached, as at 27, to the pendent members 2 upon that side of the swing, in the manner similar to the cords 21 upon 10 the other side.

With the parts constructed and arranged substantially as hereinbefore described, the operation is simple and will be readily understood when taken in connection with the 15 annexed drawings. Briefly stated, it is as follows:

As the platform 28 is swung back and forth, the cords 21 and 26 will be alternately wound upon and unwound from their respective spools and by reason of the clutch mechanism constituted by the slidable pin 17 and the cam surfaces 15 and abrupt shoulders 16 within the chamber 14 of the enlarged member 13 of each spool, the power 20 is constant and the shaft 7 and, consequently, the fan blades 9 will be continually revolved in the same direction regardless of the direction in which the platform and the pendent members 2 are moving. Attention 25 is called to Figs. 3 and 4 in which I have shown diagrammatically the movement of the fan blades as being the same regardless of the direction of movement of the platform 28 and the pendent members 2. It is 30 to be noted that the cords 21 and 26 are oppositely wound upon their spools, that is one is wound from the top and the other from the bottom. As movement is given the swing, the one spool is revolved in one direction and the other spool is revolved in the opposite direction. During this movement the pin 17 in the chamber 14 of the one spool 35 is out of engagement with the abrupt shoulders 16, as indicated in Fig. 6. During this movement the pin 17 in the opposite spool is in engagement with the abrupt shoulders 16. As soon as the platform and the pendent members 2 are moved in the opposite direction, this action is reversed and the spools, 40

consequently, moved in opposite directions 50 and both in a direction opposite to that in which they were previously revolved. Thus I attain constant power and motion to at all times revolve the shaft 7 and, consequently, the fan blades always in the same direction, 55 the clutch members automatically reversing themselves as the direction of movement of the pendent members 2 is reversed.

The freedom of movement endwise of the shaft 7 permits the cords 21 and 26 to at all 60 times wind properly upon their spools, avoiding any possibility of over-wrapping and consequent binding which would tend to interfere with the proper operation of the parts. 65

Modifications in details may be resorted to without departing from the spirit of the invention or sacrificing any of its advantages.

What is claimed as new is:—

1. In a fan attachment for swings, pendent swing members, a transverse fan shaft, spools loosely mounted on said shaft one near each end, flexible connections between said pendent members and spools adapted 75 to be oppositely wound upon the latter, and clutch mechanism coöperating with said spools to give constant revolution to said shaft in one direction, said shaft being mounted for endwise movement in its bearings. 80

2. In a fan attachment for swings, pendent swing members, a transverse fan shaft endwise movable in its bearings, spools loosely mounted on said shaft, a cord connected to opposite pendent members at one side of the swing and wound upon the adjacent spool, a cord connected with the pendent members upon the opposite side of the swing and wound in an opposite direction 85 upon the adjacent spool, and automatically reversible clutch mechanism coöperating with said spools and oppositely disposed to give constant revolution to the fan shaft in one direction regardless of the direction of 90 movement of said pendent members. 95

In testimony whereof I affix my signature.

ISAAC W. CRABTREE.
